JOHN CAMPBELL MacCALL MACLAGAN, OF GLASGOW, SCOTLAND.

SCAVENGING DEVICE FOR COMBUSTION ENGINES.

1,421,273.

Specification of Letters Patent. Patented June 27, 1922.

Application filed August 16, 1921. Serial No. 492,752.

To all whom it may concern:

Be it known that I, JOHN CAMPBELL MacCALL MACLAGAN, a subject of the King of Great Britain and Ireland, and a resident 5 of Glasgow, Scotland, have invented certain new and useful Improved Scavenging Devices for Combustion Engines, for which I have received British Patent No. 150,238 upon an application filed in Great Britain 10 February 25, 1920, and of which the following is the specification.

The invention which is applicable to combustion engines having piston rods or tail rods has for its object to provide simple and 15 effective means for ensuring complete scavenging at the end of the working stroke, the means being applicable either alone or in conjunction with other scavenging devices.

The improved device is of the type in 20 which there is provided in the piston or other rod, a portion of reduced diameter which is enclosed in a sleeve towards the opposite ends of which are series of ports. The reduced portion thus serves as a means of 25 communication between the ports. The series of ports are arranged around the periphery of the sleeve, and the one series of ports are adapted to form communication with ports in the embracing wall of the 30 cylinder cover, or in a sleeve therein, and so with an annular chamber therein, while the other series of ports are in communication with the interior of the cylinder. Scavenging air is supplied to the annular 35 chamber and passes therefrom through the ports in its walls and in the sleeve to the space within the sleeve and from thence to the interior of the cylinders at that point in the travel of the rod at which the chamber 40 ports and the coacting series of sleeve ports coincide. Now, it is apparent that were the sleeve ports communicating with the cylinder in the same axial line as the sleeve ports communicating with the chamber ports (and 45 so in the same axial line as those ports) further motion of the rod would open communication between the chamber ports and the first mentioned ports and so with the interior of the sleeve and thence by way of 50 the other sleeve ports with the atmosphere. Either therefore, the distance between the two series of ports would have to be so great that the second series could never overrun the annular chamber ports or else an enclos-

ing trunk would be required to prevent connection between the cylinder and the atmosphere. 55

According to the invention therefore, the total width of each series of ports is made rather less than half the circumference of 60 the sleeve and of the chamber wall, and while the one series of sleeve ports are positioned to coact with the chamber ports, the other series (which communicate with the cylinder) are made in axial line with the 65 spaces between these ports, and so in passing the chamber ports do not open communication therewith.

An illustrative example of the carrying out of the invention is shown on an accompanying sheet of drawings, Figure 1 being 70 a sectional elevation and Figure 2 a sectional plan on the line *a*—*b* in Figure 1.

In this example there is formed in the lower part of the piston rod *A* a part *B* of 75 reduced diameter. This is enclosed by a sleeve *C* which is held in position between the crosshead *D* and the lower end of the upper part *E* of the piston rod. Around its periphery is a series of ports *F* and a series 80 of ports *G*. The series of ports *F* communicate with the interior of the cylinder, and the ports are in axial line with the walls between the ports *G* which are adapted to coincide with ports *H* in a sleeve *J* in the 85 cylinder cover *K*, which ports communicate through its walls with an annular chamber *L* formed in the cylinder cover.

What I claim is:—

1. In an internal combustion engine, an 90 explosion cylinder having at one end a chambered cover with a port opening to the chamber in the cover, a piston rod passing through said cover and recessed in the portion thereof working in said cover, a casing 95 enclosing said recessed portion of the piston rod, said casing being apertured at longitudinally spaced points to afford ports circumferentially staggered with relation to each other, but opening to the recess in the 100 piston rod, the port toward the cylinder end of the casing being out of axial alignment with the port in the cylinder cover, while the port toward the opposite end of the casing is located in axial alignment with the 105 port in the cylinder cover and registers therewith in predetermined longitudinal position of the piston rod to establish communication

between the chamber in the cylinder cover and the explosion cylinder through the recess in the piston rod.

2. In an internal combustion engine, an explosion cylinder having at one end an angularly chambered cover with a series of inwardly opening ports, a piston rod passing through said cover and of reduced diameter in the portion working in said cover, a sleeve 10 encasing the reduced area of the piston rod, said sleeve having toward its cylinder end a series of ports out of axial alignment with the ports in the cover chamber but opening to the reduced portion of the cylinder rod,

while at its opposite end said sleeve has a 15 series of ports located in axial alignment with the ports to the cover chamber and registering therewith in predetermined longitudinal position of the piston rod to establish communication between said chamber in 20 the cylinder cover and the explosion cylinder through the passageway afforded between the reduced portion of the piston rod and its enclosing sleeve.

In testimony whereof I have signed my 25 name to this specification.

JOHN CAMPBELL MacCALL MACLAGAN.
